UNITED STATES PATENT OFFICE.

EUGENE J. STOLTZ, OF NEW YORK, N. Y.

KNIFE-SHARPENER.

1,090,421.

Specification of Letters Patent. Patented Mar. 17, 1914.

Application filed May 28, 1913. Serial No. 770,293.

To all whom it may concern:

Be it known that I, EUGENE J. STOLTZ, a citizen of the United States, residing at the borough of Manhattan, city, county, and 5 State of New York, have invented an Improvement in Knife-Sharpener, of which the following is a specification.

My present invention relates to a knife sharpener, and particularly to that class of 10 these devices in which the blade of a knife, or other tool which is to be sharpened, is drawn over and between the surfaces of adjoining sharpening disks, and the object of my invention is the provision of a sharpener of this type which is of inexpensive 15 construction, which includes members by which the sharpening disks may be turned to present new surfaces to the edge to be sharpened, and also a tool which is of such 20 a size as to be readily carried about in one's pocket.

The particular construction of my improved knife sharpener will be hereinafter more particularly described.

25 In the drawing, Figure 1 is a side elevation of my improved knife sharpener. Fig. 2 is an inverted plan of the same, and Fig. 3 is an end elevation of the same.

Referring to the drawing, it will be seen 30 that in making my improved sharpener, I preferably employ a frame 10, made of sheet metal or other similar material, in corresponding parts, adapted to be folded so as to lie in planes approximately parallel 35 to each other. One side of the frame is indicated at 11 and the opposite side at 12. This frame also includes a handle 13, by which the instrument may be readily grasped when in use, and the sides also include projections 14, 15, employed in pairs.

40 Mounted between the pair of projections 14 is a sharpening disk 16. As shown in the drawing, this is preferably mounted on a pivot 17, which is journaled in the projections 14. Similarly in the projections 15 is a sharpening disk 18 secured to a pivot 19, which is journaled in the projections 15. These sharpening disks, as indicated in the drawing, are so placed in the frame that 45 their peripheries contact with one another, and, as will be understood, these sharpening disks are preferably made of suitable hardened steel. Also within the projections 14 and secured on the pin 17, or suitably secured to one face of the sharpening disk 16, is a toothed wheel 20, which is of materially

smaller diameter than the sharpening disk 16 and is concentric therewith. The sharpening disk 18 is similarly provided with a toothed wheel 21. I also employ a toothed wheel 22 mounted on a pin 23 passing through and journaled in the sides of the frame in such a position that the teeth of the wheel 22 mesh with the teeth of the wheels 20 and 21. This toothed wheel 22, 60 as will be seen by reference to Figs. 1 and 3, projects an appreciable distance through a slot provided therefor in the edge of the frame, so that the wheel 22 may be readily revolved to turn the wheels 20 and 21, which, 65 as will be understood, also cause the sharpening disks 16 and 18 to turn, so that as often as desirable in the use of the instrument, a new surface may be presented by the sharpening disks to the edge of the tool 70 to be sharpened. I also prefer to employ a pair of lugs 24, 25, projecting laterally from the sides of the frame, and suitably secured thereto to act as guards in the use of the instrument, so as to enable the user 75 to bring the edge of the tool with sufficient friction against the sharpening disk without the liability of the tool slipping and cutting the fingers, and in order that the toothed wheel 22 may be properly maintained in 80 position within the frame, I may also employ a spacing washer 26, which is clearly indicated in Fig. 3.

I claim as my invention:

1. A knife sharpener comprising a frame, 85 sharpening disks so mounted therein that their peripheries contact with one another, wheels of smaller diameter than the sharpening disks lying beside the same within the frame, and means also secured within the frame for revolving the said wheels of smaller diameter to turn the sharpening disks.

2. A knife sharpener comprising a frame, 90 knife sharpening disks mounted therein so their peripheries are in contact with one another, a toothed wheel secured within the said frame against the side of each sharpening disk, and a toothed wheel mounted in the side of the said frame in such a position 95 that the teeth thereof mesh with the teeth of the aforesaid toothed wheels.

3. A knife sharpener comprising a frame having parallel sides, lugs in pairs projecting from the said sides, a knife sharpening 100 disk mounted between each pair of lugs so 105 that the peripheries of the said disk contact

with one another, a toothed wheel of smaller diameter than the said knife sharpening disks connected to each of the said sharpening disks between the said projecting lugs, and a toothed wheel mounted in the sides of the said frame projecting through an aperture provided therefor in one edge of the

frame, the teeth of which mesh with the teeth of the aforesaid toothed wheels.

Signed by me this 24th day of May, 1913. 10
EUGENE J. STOLTZ.
